UNITED STATES PATENT OFFICE.

WILLIAM H. PERRY, OF CONCORD, NEW HAMPSHIRE.

DESIGN FOR A MONUMENT.

SPECIFICATION forming part of Design No. 24,461, dated July 2, 1895.

Application filed June 7, 1895. Serial No. 552,034. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for Monuments, of which the following is a specification, reference being had to the accompanying drawing.

The leading features of my design include the configuration of the shaft, its ornamental top or cap piece, and the various styles of finish upon the surfaces of the different parts, is fully set forth in the following specification and claim, and clearly illustrated in the drawing accompanying and forming a part of the same, reference being had to the letters and figures, as follows:

The base 1 has four vertical sides, terminating at their tops in an obtuse frustum of a pyramid 2, upon which rests the pedestal 3, which terminates in an acute frustum of a pyramid 4, upon one or more sides of which may be formed a raised tablet 5.

The shaft has for the most part tapering sides 6, and is provided at its bottom, adjacent to the frustum of a pyramid 4, with raised tablets 7 and at the upper end of the tapering sides with raised tablets 8, the upper edge of the tablets 7 and the lower edge of the tablets 8 being beveled, as shown, re-

spectively, at 9 and 10. The upper edges of the tablets 7 rise from their corners toward their centers, where they meet an extension made in the form of a segment of a circle 11, and the lower edges of the tablets 8 are provided with notches or grooves 12. The tapering sides of the shaft 6 have each a tablet 13, distinguishable by a finish of a different character and by a heavy border-line 14.

The upper edges of the tablets 8 terminate in an acute frustum of a pyramid 15, upon which rests the cap, the vertical sides of which represent depending scallops 16, and the top of which terminates in a four-sided pyramid 17.

I also ornament my design by surfaces of a different character, and in the drawing these are designated as follows: A represents rock-work, B hammered work, and C polished work.

What I claim is—

The design for a monument, substantially as described and shown.

In testimony whereof I affix my signature in presence of two witnesses.

WILLIAM H. PERRY.
